UNITED STATES PATENT OFFICE.

JOHN D. HOGAN AND FREDERICK S. SPENCER, OF SAN FRANCISCO, CALIFORNIA.

TABLE.

Application filed March 13, 1923. Serial No. 624,852.

This invention relates to improvements in built-in features as characterized in the present practice of incorporating ironing boards, tables and pieces of household furniture in the construction of homes, dwellings and the like and resides in the provision of a novelly constructed built-in feature, such as a table, which may be readily incorporated in the wall of a building with a minimum of expense and labor.

An object of the invention is to provide a support of the character described which, in this instance, is characterized as a table, the mounting of which consists of a case or cabinet adapted to be set flush in the wall of the structure and into and out of which the support or table may be moved in an easy and convenient manner.

An important point of advantage attending the use of the invention is that it may be set beneath the now commonly used wainscoting strip which latter is usually four feet above the floor and the space above four feet over the cabinet may be utilized for a large window. In other types of wall tables or seats the cabinet or case extends a foot or more above this strip and we are not aware of a wall device or unit of the nature of our invention which is installed beneath the wainscoting strip. Where the device extends above the strip there is little or no space left above the device for a window and only a small window may be provided. With our device, less work and time are required to build in the unit than is the case with units such as described wherein the units extend above the wainscoting strip and furthermore in our construction the appearance of the room is less disturbed due to not having to cut through or interrupt the said wainscoting strip.

Another object is to provide a construction of the character described which is characterized by novel means for facilitating the folding or collapsing of the table in small compass in concealed position in the wall and for also facilitating the extension of the table for use.

More specifically the invention relates to the provision of a spring arrangement associated with a cabinet or wall recess and table of the character described, which arrangement resists the movement of the table into collapsed or folded position, securely holds the table in collapsed position, assists in the

movement of the table into extended position and provides for the construction of a unit which may be made to take up less space than the ordinary wall table and may be installed at less inconvenience and expense than similar arrangements.

With the above mentioned and other objects in view, the invention consists in the novel construction and combination of parts hereinafter described, illustrated in the accompanying drawings, and set forth in the claim hereto appended, it being understood that various changes in the form, proportion, size and minor details of construction within the scope of the claim may be resorted to without departing from the spirit or sacrificing any of the advantages of the invention.

Referring to the drawings:

Fig. 1 represents a perspective view of built-in construction made up in accordance with this invention showing the support in this instance a table, as when extended.

Fig. 2 is a vertical sectional view of the structure showing the table as when in collapsed position.

Fig. 3 is a fragmentary vertical sectional view showing the table in extended position.

Fig. 4 is a detail fragmentary sectional view showing the manner of mounting the table.

We wish it understood that while we have selected a table to illustrate the manner in which we may provide for the wall mounting of a household article such as a shelf support, ironing board, table, seat and the like, that elements other than the table may be employed without in any way departing from the spirit and scope of the invention as will be hereinafter more fully described.

In carrying out the invention, we provide a cabinet or casing 1, made up of side pieces 2, back wall 3, top and bottom pieces 4, and a front wall 5. The dimensions of this cabinet depend upon the characteristics of the support or piece which is to be associated with the cabinet. The front wall will terminate short of the top of the cabinet leaving an open space providing for the movement of the table into and out of concealed position. The cabinet is constructed so that it may be countersunk or set flush in the wall. The support 7, in this instance, a table of rectilinear outline, is provided with trunnions 8 near its inner end, which trunnions

pivot in slides 9 which are vertically slideable in grooves 10 provided in the sides of the cabinet. A reinforcing strip or piece 11 is provided across the inner end of the table at the under side thereon and this strip or piece is adapted to engage the upper edge of the front wall when the table is in extended position, whereas the upper side of the table at its inner end is adapted to engage under a stop bar 12 which is extended transversely across the front of the back wall just above the upper edge of the front wall. On the under side of the table adjacent its outer end there is provided a suitable handle 13.

Spring means generally designated 14, is mounted in the cabinet and arranged so that it will resist the movement of the table into concealed position, hold the table in such position with the outer, (then upper) edge of the table pressing against the under side of the top piece 4 of the cabinet, and which will assist in the movement of the table into extended position. One embodiment of this spring device, as shown in the drawing, comprises an elongated casing 15 which extends vertically along the center of the rear wall from the stop bar to the top of the cabinet and may be secured thereto in any suitable manner. A helical retractile spring 16 is secured by a slideable fastening 17 to the top piece of the cabinet and is loosely mounted in the casing 15. The lower end of the spring extends beyond the lower end of the casing and is attached by a suitable fastening 18 to the inner end of the table, the pivot or trunnion being between this point of attachment of the spring and a mediate portion of the table so that a leverage action 40 may be provided through the action of the spring. It will be noted that the stop bar 12 is constructed with relation to the spring housing such that the spring extends through and beneath the stop bar 12 whereby it may effect the leverage action necessary.

When the table is in collapsed position as shown in full lines in Fig. 2, it is under spring tension and held against the top of the cabinet. To extend the table, it is grasped by the handle and moved downwardly sufficiently to facilitate the outwardly swinging movement of the upper end thereof. When the upper end of the table has been extended out of the cabinet the table will swing on its pivot, and due to the action of the spring, will be lifted at its inner end. By swinging the table on its trunnions as the slides 9 are moved upwardly in the grooves 10, the table will be extended as shown. The table is held secure by its engagement with the upper edge of the front wall and the stop member as shown in Fig. 2.

To move the table into collapsed and concealed position, it is swung on its trunnions

into upright position and forced downwardly at the same time, so that the inner end moves downwardly in the cabinet against the action of the spring and by swinging the outer end of the table under the top of the cabinet and pushing inwardly as far as the table will go, the collapsing movement of the table is completed and said table is concealed in the wall. If desired a door or closure 20 may be provided for the opening 75 in the cabinet.

As shown in Fig. 1 the cabinet of the unit is set in a wall A below the wainscoting strip B. This strip is usually set about four feet from the floor and by setting the device 80 of our invention below it a great deal of space above the strip is available for a large window as shown at C. In all other types of wall tables and the like of which we are aware, the construction and arrangement is 85 such that said devices extend a foot or more above the wainscoting strip. This requires extra work and time in cutting through and interrupting the strip and leaves space for but a small window above the table. The 90 peculiar manner of mounting the table in the cabinet and the mode of use thereof permit us to construct a device as a small compartment having the advantages hereinbefore set forth.

To prevent injury to the spring, a slideable fastening 17 is provided in the form of a sleeve 21 which is slideable in an end opening slot 22 in the table and through an opening 23 in the reinforcing strip 11. Extending through the sleeve is a member 24 having an eye 25 on one end and a stop member 26 removably secured to the other end, said spring being attached to said eye.

When the table is in extended position, the tension on the spring is relieved and the fastening 17 will drop into position shown in Fig. 3, of the drawing, whereby upon first movement of the table into concealed position and the inner end of the table is moving arcuately, in order that the table may be brought into position to be forced downwardly into the cabinet, the spring will not be placed under tension. When the inner end of the table is in position to be moved bodily outward into the cabinet, the stop member 26 engages with the member 11 and upon continued downward movement of the table, the spring is placed under tension. By reason of the slot 22 in the table, through which slot the fastening 17 extends, the table may be removed for the purpose of repair to the spring device or for other purposes, upon removal of the strip 11 from the table, said strip 11 being preferably secured in place 125 by screws.

Another point of advantage in the construction of our invention is that the space beneath the table is free and unobstructed and provides ample leg and storage space.

This is due to the fact that no bracing or supporting means are necessary beyond the means provided in the cabinet.

We claim:—

- 5 A casing having an opening on one side, the lower extremity of which opening is located nearer to the upper end of the casing, an article of furniture movable through the opening from a position within the casing 10 into a position of use extending outwardly from the casing, a stop member in the casing for limiting the movement of the article of furniture into its extended position, slide members movable up and down in the casing 15 and to which said article of furniture is piv- oted, said article of furniture having an opening therein adjacent to its inner extremity, a retractile spring one end of which extends through said opening and the other end of which is connected with the casing at a point above the lower extremity of the first named opening and a stop member on the lower extremity of the spring, which stop member is engaged by the article of furniture as the latter is moved into position within the casing to place the spring under tension.

JOHN D. HOGAN.
FREDERICK S. SPENCER.
